JULIUS S. POPPER, OF ELIZABETH, NEW JERSEY

LEAF HINGE CLIP

Application filed November 3, 1931. Serial No. 572,847.

This invention relates to clips, and more particularly to leaf hinge clips.

In the use of hinged leaves for reference matter, it is frequently necessary to remove these leaves from their pivotal connection in holders in which they are more or less permanently positioned, for certain reasons, as for instance, to make changes thereon, and to then replace them. In such cases it is desirable that these operations be performed easily and expeditiously.

It is an object of this invention to facilitate the removal and replacement of the leaves by providing a clip to hingedly and detachably connect such leaves.

This and further objects will be apparent from the following description, when considered in connection with the accompanying drawing in which certain modifications 20 of the invention are illustrated.

Referring to the drawing, Figure 1 is a sectional view showing one modification of the improved clip and a fragment of its attached leaf or card; Figs. 2, 3 and 4 illustrate other modifications of Fig. 1; and Fig. 5 is a plan view of a series of cards and their holder showing the improved clips in attached position.

In the drawing, in which similar elements 30 of the improved device are referred to by like characters, throughout, the numeral 5 is applied to a leaf or card which is to be hingedly and detachably secured in position. The leaves 5 are provided with slits 6 which may be of a number to correspond to that of the 35 clips to be used. These slits are spaced a proper distance from the edges of the leaf for the accommodation of the clips as will be presently described. Either of the arms of 40 the clip is adapted to be inserted through the slit.

The clip 7 consists of a resilient metal strip which is bent upon itself to provide two substantially parallel arms 8 and 9. The space 45 between these arms throughout their major portion is narrow so that they closely embrace and clamp the sides of the leaf 5. The arm 8 is provided with an arcuate portion 10 near its end. The extremity 11 of this arm 50 is bent in a direction opposite to that of the

portion 10, and is shown as being of substantially semi-circular formation. The arms 9 in Figs. 1, 2 and 3 are shown as being substantially straight, and their ends are formed into an outwardly extending hook portion 12. 55 In Fig. 1 the arm 9 is slightly shorter than its companion arm 8; in Fig. 2 the arm 9 substantially coterminates with the arm 8; and in Fig. 3 the arm 9 extends beyond the arm 8. 60

In the modification shown in Fig. 4, the arm 9 is provided with an arcuate shaped portion 13 which lies intermediate the straight portion of said arm and its hooked portion 12. The arcuate portions 10 and 13 of Fig. 4 are of similar shape and together form a substantially broken circle. 65

The opening between the members 11 and 12 is less than the distance between the parallel straight portions of the clip. The pocket between the arcuate portion 10 of the arm 8 and adjacent surfaces of the arm 9 forms a hinge joint in which a transverse pintle or rod may register so that the leaf 5 may be rotated on said pintle, as will presently appear. 75

For the purpose of illustration the improved clip is shown in connection with a holder such as indicated at 14 in Fig. 5. This holder may be enclosed in any suitable container, and carries a series of leaves or cards 5 bearing reference matter on both of their surfaces. The bottoms of the cards may be provided with indexing tabs whereby they 80 may be readily identified. The cards or leaves 5 are hinged about transverse and horizontally disposed pintles 15, which may be pivoted at one end to a side rail 16 and the other ends of the pintles may register in slots in 85 the opposite side rail 17. The last-mentioned rail may have a lateral slidable member 18 which may serve to close or open the slots into which the ends of the pintles 15 fit to lock or release the pintles. 90

The transverse pintles 15 extend through the hinged joint formed near the extremities of the arms 8 and 9 so that the cards or leaves 5 may be readily rotated thereon. The cards 5 may be quickly detached from their pivotal 100 connection by simply pulling them in a down-

ward direction, thus causing the ends of the arms to be forced apart and permitting the withdrawal of the clip from the pintle. To restore the card again to its pivoted mounting on the transverse pintle or rod, it is only necessary to move it inwardly until the ends of the clip engage the pintle. Pushing the clip against the rod at this time will cause the arms of the clip to spread apart and snap over the pintle into pivoted engagement therewith.

10 What is claimed is:

A hinged leaf including a card having a slit near one margin, a pintle member about which said card member may be rotated, and a clip formed of a strip of resilient material passed through said slit and bent to form a bight within the slit, the bent sides of said strip clamping the surfaces of the card, and having a portion near the free end of at least 15 on of said sides of the strip being curved to form with the other side a hinge joint to engage said pintle, and hooked portions at the extremities of the clip bent in opposite directions from each other and having an opening 20 therebetween leading to the hinged joint, the hooked portions forming a snap through which the hinged leaf is engaged with and disengaged from the pintle member.

25 In testimony whereof, I have signed my name to this specification this 2nd day of November, 1931.

JULIUS S. POPPER.
